Frank Stringer, ^{Inventor}

By, Herbert E. Smith

Attorney

Patented Dec. 22, 1925.

UNITED STATES PATENT OFFICE.

FRANK STRINGER, OF KELLOGG, IDAHO.

CIGARETTE BOX.

Application filed February 14, 1925. Serial No. 9,307.

To all whom it may concern:

Be it known that I, FRANK STRINGER, a citizen of the United States, residing at Kellogg, in Shoshone County, and State of Idaho, have invented certain new and useful Improvements in Cigarette Boxes, of which the following is a specification.

My present invention relates to improvements in cigarette boxes in the class of 10 special receptacles and packages. Although I have illustrated the physical embodiment of my invention in a cigarette package or box, it will be understood that the invention may be embodied in other packages for various uses. The primary object of my invention is the provision of means in the form 15 of a duplex projector-strip whereby the initial cigarettes removed from the box or pack may be so removed with facility and convenience after the package has been torn away to expose the end or ends of some of the cigarettes.

The projector-strip is designed to be packed with the cigarettes in the receptacle 20 therefore and is provided with duplex projecting tabs that are accessible from either corner of the package when opened, thus providing a selective use for the convenience of the cigarette user. After the first 25 or initial cigarette or cigarettes are withdrawn from the pack, the remaining cigarettes may with convenience be withdrawn in the usual manner.

My invention consists in the combination 30 with a standard form or type of cigarette box or package, of a specially formed projector strip which is incorporated with the pack of cigarettes for use as will hereinafter be more fully described and claimed.

In the accompanying drawings I have illustrated one complete example of the physical embodiment of my invention wherein the parts are combined and arranged in accordance with the best mode I have thus far 45 devised for the practical application of the principles of my invention.

Figure 1 is a perspective view of a box or package of cigarettes with which the device of my invention is embodied, part 50 of the package being torn away to disclose the use of one of the duplex projector-tabs.

Figure 2 is a sectional view through a cigarette box showing the operation of the projector-strip and its relation to projected 55 cigarettes.

Figure 3 is a detail perspective view of one of the duplex projector strips.

In the drawings for convenience of illustration and description of my invention, I have shown a standard form or type of cigarette box or package 1 with the usual bottom 60 2 and top portion 3, the latter being torn away in Figure 1 to disclose the cigarettes at 4 and the manner of projecting them.

The duplex projector-strip is preferably 65 made up of light paste-board or comparatively heavy paper in approximate U-shape and of the proper size to fit within the cigarette box or package.

The base 5 of the projector-strip lies flat 70 upon the bottom 2 of the box and said base is provided with a pair of side arms 6 and 7 which extend parallel with the two end rows of the cigarettes in the pack as shown in Figure 2. At the free ends or extremities of the side arms are provided projector-tabs 8 and 9, which when the strip is packed in the box lie beneath the top 3 of the box and project toward each other over the ends 75 of the outer rows of the pack.

At the junctions of the side arms with the base of the strip are provided V-shaped folds 10 and 11, which when the strip is packed with the cigarettes lie flat against the bottom 2 of the box with the end rows of the 80 cigarettes resting upon them as indicated at the right in Figure 2.

Near the upper free ends of the strip are provided perforations 12 and 13 which 85 extend in rows transversely of the arms of the strip to facilitate tearing off of either or both of the tabs after they have been used, to remove them as obstructions, from the interior of the box.

The utility of the duplex projector-strip 90 will be apparent from an inspection of the drawings. After one corner of the top of the package has been torn away, as indicated in Figure 1, from a selected corner of the box, the tab is accessible and may readily 95 be grasped. By pulling on the selected tab, the V-shape fold is caused to be extended to an angular position as indicated at the left in Figure 2, and this angularly extending movement of the fold projects one or more 100 rows of the cigarettes at that end of the box, lifting or projecting the cigarettes as indicated in Figures 1 and 2. The cigarettes wanted may then readily be grasped at 105 their ends by the fingers and thumb and 110

withdrawn from the pack. The used tab may then be torn away on the perforated line as 12, to remove it from the box, and the remaining cigarettes will be accessible for 5 ready withdrawal from the box in the usual manner. By the use of this duplex projector strip either of the upper corners of the box may be torn away for access thereto and a projector-tab will be found ready for 10 convenient use, the box being retained as a container for the remaining cigarettes.

Having thus fully described my invention what I claim as new and desire to secure by Letters Patent is:—

15 1. A duplex projector-strip for use in cigarette packages comprising a base, side arms and normally flat V-shaped folds at the junction of said base and arms, and fold-

able pull tabs at the free ends of said arms.

2. A duplex projector-strip for use in 20 cigarette packages comprising a base, side arms having each a row of perforations near their free ends, normally flat V-shaped folds at the junction of said base and arms and adapted to lie on said base, and foldable 25 pull tabs at the ends of said arms.

3. In a cigarette pack a duplex projector-strip having a base and folded V-shaped portions lying flat thereon beneath the end rows of cigarettes, side arms integral with 30 said folds and lying parallel with the cigarettes, a row of transverse perforations in each arm near its free end, and foldable pull tabs at the free ends of said arms.

In testimony whereof I affix my signature.

FRANK STRINGER.
